UNITED STATES PATENT OFFICE.

HARRY B. SMITH, OF NEW YORK, N. Y.

DESIGN FOR A BOX-BLANK.

SPECIFICATION forming part of Design No. 31,984, dated December 12, 1899.

Application filed November 11, 1899. Serial No. 736,701. Term of patent 14 years.

To all whom it may concern:

Be it known that I, HARRY B. SMITH, a citizen of the United States, residing at New York, (Brooklyn,) in the county of Kings and State 5 of New York, have invented and produced a new and original Design for Box-Blanks; and I do hereby declare the following to be a full, clear, and exact description of the same, reference being had to the accompanying specification and drawings, forming a part thereof.

My invention consists in a new and original design for box-blanks and is illustrated in the accompanying drawings, in which—

Figure 1 is a top plan view of a box-blank 15 made according to my design. Fig. 2 is a central longitudinal sectional view.

The leading feature of my design consists of a blank or body portion made substantially rectangular in plan view with rounded 20 or heart-shaped corners, said blank being provided with wings at each side and at each end.

Referring to the drawings, the reference-numeral 1 designates the body of the blank, which is made substantially rectangular in 25 shape and having rounded or heart-shaped corners 2. The body of the blank is provided at each end with integral wings 3, and the

two sides of the body are each provided with similar integral wings 4. As shown in the drawings, the said side and end wings 3 and 4 are made integral with the body 1; but at the lines of connection between the said body and wings the blank is slightly cut or scored, as shown at 5 and 6. The wings 3 and 4 are of substantially the same width; but in length 35 they are slightly shorter than the sides and ends, respectively, of the body portion of the blank, as shown, so that the adjacent inner corners 7 of the said wings are separated or removed from each other. The opposite ends 40 8 and 9 of the side and end wings terminate in straight lines taken substantially parallel with the scorings 5 and 6, respectively, so as to form substantially angular openings at the four corners of the blank.

What I claim is—

The design for a box-blank substantially as shown and described.

In testimony whereof I affix my signature in presence of two witnesses.

HARRY B. SMITH.
